Primary Examiner—Sandra L. Morris*Assistant Examiner*—Nanda Bondade*Attorney, Agent, or Firm*—Brinks Hofer Gilson & Lione; G. Peter Nichols[57] **CLAIM**

The ornamental design for a box blank with a removably attached lid blank, as shown and described.

DESCRIPTION

FIG. 1 is a front elevational view of a box blank with a removably attached lid blank showing our new design; the rear view being a mirror image;

FIG. 2 is a top view;

FIG. 3 is a bottom view;

FIG. 4 is a left side view; and,

FIG. 5 is a right side view.

The broken lines shown on FIG. 1 represent fold lines.
